ENGINE MOUNTING AND CONTROL SYSTEM

Elmer C. Kiekhaefer, Cedarburg, Wis.

Application March 24, 1949, Serial No. 83,250

16 Claims. (Cl. 115—18)

1

This invention relates to outboard motors and particularly to the manual control mechanism for outboard motors having a transmission system or other means for controlling the operation of the propeller.

A principal object of the invention is to improve the control of the propeller and the steering of the motor and boat in a single control member.

A further object of the invention is to prevent the vibration of the motor and gears from reaching the control member connected thereto.

Another object is to provide a more positive motor control which will respond immediately to the operator's control.

Another object is to provide for the full directional control of the propeller in a single control handle which will allow the operator of a boat greater freedom as when approaching a dock.

These and other objects and advantages of the invention will be more fully set forth in the following description of the invention as illustrated in the accompanying drawings.

In the drawings:

Figure 1 is a side elevation of an outboard motor with portions thereof broken away and sectioned to show the gear shift mechanism and control means therefor;

Fig. 2 is an enlarged front elevation of the lower end of the outboard motor partially sectioned on lines 2—2 of Fig. 1 and showing the gear shift mechanism;

Fig. 3 is a plan view of a part of the control handle showing the mounting therefor; and

Fig. 4 is a view similar to Fig. 1 showing the control handle in the raised, reverse position.

The outboard motor shown in the drawings comprises the engine 1 supported upon the upper end of the hollow cast housing 2, the underwater gear case 3 secured to the lower end of housing 2 and the propeller 4 mounted on the shaft 5 journally carried by gear case 3. The clamp bracket 6 by which the motor is removably secured to the transom of a boat, not shown, pivotally supports an intermediate swivel bracket 7 which carries the motor, as will be described, for turning on a vertical axis for purposes of steering.

The transverse pin 8 extending through brackets 6 and 7 connects the same and provides for tilting of the motor and bracket 7 relative to bracket 6 and the boat, not shown, to raise propeller 4 out of water and to allow the lower end of the motor to pass over underwater obstruc-

2

tions. The lower removable pin 9 is selectively disposed in a corresponding pair of the series of holes 10 in bracket 6 to provide for the usual tilt adjustment of the motor.

5 The drive shaft 11, disposed vertically within the hollow cast housing 2, is connected by means of spline connection as at 12 to the lower end of engine crankshaft 13 extending downwardly into the upper end of housing 2. The lower end of shaft 11 extends downwardly into gear case 3 and carries the beveled drive gear 14 at the lower end thereof.

10 The forwardly and rearwardly disposed beveled gears 15 and 16, respectively, are supported by bearings 17 within gear case 3 and mesh with drive gear 14 for rotation oppositely of each other. Gears 15 and 16 are disposed on and support shaft 5 for free rotation with respect thereto and are adapted to be rotatively engaged 15 selectively with shaft 5, as will be described, to rotate the shaft and propeller 4 in either direction as desired for propulsion of the boat forwardly or in a reverse direction. When both gears 15 and 16 rotate freely of shaft 5, propeller 4 is inoperative and the motor is in "neutral," 20 as will also be described.

15 The splined clutch element 18 is carried on shaft 5 for rotation therewith and is axially movable thereon and disposed between the positive engagement clutch faces 19 of gears 15 and 16. The opposite ends of element 18 carry clutch faces 20 which are selectively engageable with the respective complementary face 19 of the corresponding gear 15 or 16.

20 A control mechanism is provided by which element 18 is moved on shaft 5 to engage either gear 16 or 17 for rotation of shaft 5 by engine 1 through drive shaft 11 in either direction or to dispose element 18 between gears 15 and 16 without engagement with either gear 15 or 16 for the non-rotation of shaft 5. The control mechanism comprises the control arm 21 carried by brackets 6 and 7, as will be described, and the control rod 22 connecting arm 21 and arm 23 of the bell crank 24 pivotally disposed within gear case 3.

25 The arm 23 of bell crank 24 is bifurcated and carries at the ends thereof the lugs 26 which oppositely engage either side of the annular ring 27 of element 18.

Movement of the forward end of control arm 21 downwardly lifts rod 22 to move arm 23 of crank 24 rearwardly and effect the rotative engagement of gear 16 and shaft 5. By lifting control arm 21 to an intermediate position clutch element 18 is disengaged from gear 16, and shaft

3

5 and the propeller 4 are out of driving connection with engine 1 and in a "neutral" position. By raising control arm 21 to the uppermost position, as shown in Fig. 4, clutch element 18 is brought into engagement with gear 15 for the opposite rotation of shaft 5 and propeller 4.

The control bracket 28 carried by the swivel support bracket 7 pivotally supports arm 21, as described above, by means of the transverse pin 29 passing therethrough. Detent means are carried by bracket 28 comprising the bearing 30 and the spring 31 urging bearing 30 into engagement with any one of three detents 32 in the side of a portion of arm 21. Each bearing 30 provides releasable means yieldably securing arm 21 selectively in either of the three control positions above described.

The horizontally disposed circular plate 33 is rotatably mounted on the vertical sleeve 34 carried by swivel bracket 7. Plate 33 supports bracket 28 to provide for rotational movement of arm 21 to the right or left of the operator in a horizontal plane so that arm 21 may also be utilized, as will be described, to serve as a tiller.

Drive shaft housing 2 is provided with upper and lower spaced forwardly projecting bosses 35 and 36 formed integrally therewith by which the housing is mounted for steering on the respective upper and lower ends of sleeve 34. The rubber bushings 37 interposed between sleeve 34 and the housing are provided within each boss 35 and 36 for their resiliency and to absorb the vibration of engine 1 which would otherwise be transmitted through brackets 6 and 7 to the boat, not shown.

Plate 33 is cut away as at 38 and carries the depending ears 39 on either side of housing 2 adjacent the spring seats 40 formed within the opposite sides of the housing. The springs 41 are disposed between corresponding ears 39 and seats 40. The springs connect arm 21 and the motor while preventing shocks and vibration of the motor from passing to plate 33 and serve to effect turning of the motor on sleeve 34 upon rotation of plate 33 on sleeve 34 by movement of tiller control arm 21 to the right or left.

The rubber cushions 42 and 43 are carried by swivel bracket 7 in frictional engagement with the upper and lower faces of plate 33 to yieldably secure plate 33 and control bracket 28 in a given position as when the operator's grasp of tiller control arm 21 is temporarily released.

The upper cushions 42 are carried by the free end of the resilient arm or plate 44 which latter is secured at its opposite end to swivel bracket 7. The adjustment screw 45 carried by bracket 7 through the resilient leaf spring 46 which bears upon arm 44 adjustably deflects the free end of arm or plate 44 carrying cushions 42. By turning screw 45 the upper cushions 42 may be variably urged downwardly toward cushions 43. Plate 33 is disposed between cushions 42 and 43 so that the variable pressure applied to the upper cushions 42, as described, provides for the desired adjustment of the frictional engagement of the cushions with plate 33. Cushions 42 and 43, and plate 33 provide friction means yieldably securing control bracket 28 and control arm 21 against pivotal movement on sleeve 34 and through springs 41 serves to secure the motor in the selected position for steering.

The bore 47 within the forward wall of housing

4

2 and gear case 3 registers with the lower end of sleeve 34 and extends downwardly in alignment therewith to communicate with the interior of gear case 3. Control rod 22 is disposed within bore 47 to connect tiller control arm 21 and crank 24, as previously described.

In the operation of the motor the torque vibration of engine 1 causes a vibration of the motor on a vertical axis which is close to or coincident with the axis of sleeve 34 on which the motor is mounted for steering. Rod 22 extends axially through sleeve 34 and substantially along the axis of vibration so that the vibration referred to cannot be transmitted to tiller control arm 21 in any position of the motor in steering or of the gear mechanism. The rubber cushion element 48 interposed between tiller control arm 21 and rod 22 flexibly connects the same and serves to prevent vibrations of gears 14, 15 and 16 from being transmitted through crank 24 and rod 22 to arm 21.

In the operation of the motor in reverse the thrust of propeller 4 is directed forwardly tending to tilt the motor on pin 8 and allowing the propeller to lift itself to the surface of the water. The latch 49 is pivotally carried by swivel bracket 7 to engage selectively adjustment pin 9 carried by clamp bracket 6 securing the motor thereto. One end of latch 49 is disposed within sleeve 34 intermediate its ends. The upper and lower abutment collars 50 and 51 are disposed on rod 22 to engage latch 49 so that in the "reverse" position of tiller control arm 21 the upper collar 50 causes latch 49 to engage pin 9 and lock and the motor to prevent tilting and moving control arm 21 to the "forward" position raises collar 51 to effect disengagement of latch 49 and pin 9.

The invention provides for full control of the steering of the motor and gear shift mechanism in a single control arm which is mounted on and carried by the boat independently of the motor. The connecting elements between the motor and control arm which respond to movement of the latter in different directions provide positive, direct actuation of the motor while at the same time any vibrational movement of the motor is prevented from reaching the control arm in the hands of the operator.

Various embodiments of the invention may be employed within the scope of the accompanying claims.

I claim:

1. In an outboard motor, a dirigible motor unit including an engine and an underwater propeller and reversing mechanism, a stationary bracket having an open sleeve pivotally supporting said motor unit for relative movement on a vertical steering axis, said motor unit being subject to torque vibration on said steering axis, a control arm including a control bracket pivotally carried by said sleeve independently of said motor unit, said control arm being adapted to pivotally move said control bracket therewith on said sleeve and being movable with respect to said control bracket in another direction, friction means yieldably securing and normally resisting pivotal movement of said control bracket on said sleeve and with respect to said stationary bracket, resilient means connecting said control bracket and said motor unit for steering by movement of said control arm and control bracket in the direction overcoming said yieldable friction means, and means passing through said sleeve connecting said arm and the reversing mecha-

nism of said motor unit for control of the latter by movement of said arm in said another direction independently of the steering movement effected through said control bracket and unaffected by the vibration of the motor unit on its steering axis.

2. In an outboard motor, a dirigible motor unit including an engine, an underwater propeller and a propeller reversing mechanism, a stationary bracket pivotally supporting said motor unit for relative movement on a vertical steering axis, said motor unit being subject to torque vibration on said steering axis, a control bracket carried by said stationary bracket for pivotal control movement independently of said motor unit on said axis, a control arm carried by and adapted to pivotally move said control bracket therewith on said vertical axis and being movable with respect to said control bracket in a direction other than that of said pivotal movement, friction means yieldably securing and normally resisting pivotal movement of said control bracket with respect to said stationary bracket, resilient means connecting said control bracket and said motor unit for steering the latter by said pivotal movement of said control arm and control bracket together in a direction overcoming said yieldable friction means, and a control rod extending through said stationary bracket and connecting said arm and the reversing mechanism of said motor unit for control of the latter by movement of said arm in said other direction independently of the steering movement effected through said control bracket and substantially free of the torque vibration of the motor unit on its steering axis.

3. In an outboard motor, the combination of a steerable motor unit including an engine and an underwater propeller and reversing gear unit, a drive shaft housing supporting said engine at its upper end and carrying said gear unit at the lower end thereof, a swivel bracket having an open sleeve pivotally supporting said motor unit, a clamp bracket pivotally carrying said swivel bracket with said sleeve normally disposed vertically for steering of said unit thereon and for tilting said unit and swivel bracket on a transverse axis forwardly of the motor unit whereby said propeller and gear unit may be removed out of water, a manual actuating arm for said gear unit disposed forwardly of the motor unit and adjacent the upper open end of said sleeve, a crank lever disposed beneath the lower end of said sleeve to actuate said reverse gear unit, locking means carried by said swivel bracket adjacent the lower end of said sleeve and selectively engageable with means on said clamp bracket to prevent relative movement of said brackets, a control rod connecting said actuating arm and crank lever axially through said sleeve, and means on said control rod to actuate said locking means carried by said swivel bracket whereby tilting of the motor is prevented when said actuating arm and crank lever are moved to a reverse gear position.

4. In an outboard motor of the class described, a steerable motor unit including an engine, an underwater propeller and reversing gear unit having a clutch actuating crank, a drive shaft housing supporting said engine at the upper end and carrying said underwater gear unit at the lower end and having vertically spaced and aligned support bearings forwardly thereof, said motor unit being subject to torque vibration on the vertical axis of said support bearings, a

swivel bracket having an open sleeve disposed between and in alignment with said bearings to support said motor unit on said bearings, a clamp bracket carrying said swivel bracket for tilting of said motor unit and swivel bracket on a transverse axis forwardly of the motor unit whereby said underwater unit may be raised, a manual control arm including a control bracket carried independently of said motor unit on said sleeve near the upper end thereof and for pivotal movement thereon, said control arm being carried by and adapted to pivotally move said control bracket therewith on said sleeve and being movable with respect to said control bracket in a direction other than that of said pivotal movement, friction means yieldably securing and normally resisting pivotal movement of said control bracket with respect to said swivel bracket, tilt locking means carried by said clamp bracket and said swivel bracket adjacent the lower end of said sleeve and selectively engageable to limit and prevent relative movement of the motor unit and swivel bracket with respect to the clamp bracket on said transverse axis from a selected position disposing said sleeve vertically for normal operation and steering by movement of the motor unit on the vertical axis of said sleeve, resilient connecting means between said control bracket and the motor unit for steering the latter by pivotal movement of said control arm including said control bracket together on said sleeve in a direction overcoming said yieldable friction means, and a control rod extending axially through said sleeve and operatively connecting said control arm and crank for control of said gear unit by movement of said arm in another direction independently of any steering movement on said sleeve effected through said control bracket and engageable with said locking means carried by said swivel bracket whereby tilting of the motor unit is prevented when said control lever is moved in said another direction to a reverse drive position.

5. In an outboard motor of the class described, a steerable motor unit including an engine, an underwater propeller and reversing gear unit having a clutch control crank, a drive shaft housing supporting said engine at the upper end and carrying said underwater unit at the lower end, and having vertically spaced and aligned support bearings forwardly thereof, said motor unit being subject to torque vibration on the vertical axis of said support bearings; a swivel bracket having an open sleeve supporting said motor unit on said bearings at opposite ends of the sleeve, a clamp bracket carrying said swivel bracket for tilting of said motor unit and swivel bracket on a transverse axis forwardly of the motor unit whereby said underwater unit may be raised, a manual control arm carried independently of said motor unit on said swivel bracket, tilt locking means carried by said clamp bracket and said swivel bracket adjacent the lower end of said sleeve and selectively engageable to limit and prevent relative movement of the motor unit and swivel bracket with respect to the clamp bracket on said transverse axis from a selected position disposing said sleeve vertically for normal operation and steering by movement of the motor unit on the vertical axis of said sleeve, and a control rod connecting said control arm and crank axially through said sleeve for control of said gear unit by movement of said lever independently of any steering movement of the motor unit on said sleeve and engageable with

said locking means carried by said swivel bracket whereby tilting of the motor unit is prevented when said control arm is moved to a reverse drive position.

6. In an outboard motor of the class described, a steerable motor unit including an engine, an underwater propeller and reversing gear unit having a clutch control crank, a drive shaft housing supporting said engine at the upper end and carrying said underwater gear unit at the lower end, and having vertically spaced and aligned support bearings forwardly thereof, said motor unit being subject to torque vibration on the vertical axis of said support bearings; a swivel bracket having an open sleeve supporting said motor unit on said bearings at opposite ends of the sleeve for steering movement, a hollow pivot pin passing through said sleeve and said bearings, a clamp bracket carrying said swivel bracket for tilting of said motor unit and swivel bracket on a transverse axis forwardly of the motor unit whereby said underwater unit may be raised, a manual control arm including a control bracket carried independently of said motor unit on said pin near the upper end thereof and for pivotal movement thereon, said control arm being carried by and adapted to pivotally move said control bracket therewith on said pin and being movable with respect to said control bracket in a direction other than that of said pivotal movement, manually releasable means normally securing said control arm and said control bracket against relative movement in said other direction, friction means yieldably securing and normally resisting pivotal movement of said control bracket with respect to said swivel bracket, tilt-locking means carried by said clamp bracket and said swivel bracket adjacent the lower end of said sleeve and selectively engageable to limit and prevent relative movement of the motor unit and swivel bracket with respect to the clamp bracket on said transverse axis from a selected position disposing said sleeve vertically for normal operation and steering by movement of the motor unit on the vertical axis of said sleeve, resilient connecting means between said control bracket and the motor unit for steering the latter by pivotal movement of said control arm including said control bracket together on said pin in a direction overcoming said yieldable friction means, a control rod connecting said control arm and crank axially through said pin for control of said gear unit by movement of said arm in said other direction against said releasable means and independently of any steering movement on said sleeve effected through said control bracket, and means on said control rod engageable with said locking means carried by said swivel bracket whereby said motor unit is locked against tilting when said control arm is moved in said other direction to a reverse drive position.

7. An outboard motor, comprising a steerable motor unit including an engine and an underwater propeller and reversing gear unit, a drive shaft housing supporting said engine at its upper end and carrying said gear unit at the lower end thereof, a bracket having an open sleeve pivotally supporting said motor unit, a manual actuating arm for said gear unit disposed forwardly of the motor unit and adjacent the upper open end of said sleeve, a crank lever disposed beneath the lower end of said sleeve to actuate said reverse gear unit, and a control rod connecting said ac-

tuating arm and crank lever axially through said sleeve.

8. An outboard motor, comprising a steerable motor unit having an engine, a forward and reverse gear transmission and an underwater propeller with a housing extending downwardly from the engine to carry the propeller, a swivel bracket having an open sleeve normally disposed vertically for pivotally supporting said motor unit upon a substantially vertical steering axis, a clamp bracket adapted to be removably clamped to the transom of a boat and pivotally carrying said swivel bracket upon a horizontal transverse axis forwardly of the motor unit for tilting of the latter to raise the propeller from the water and to accommodate boat transoms of different angular position, means to secure said brackets in adjusted angular position for forward drive of said propeller while providing for tilting of the motor unit in a direction moving the propeller rearwardly relative to the engine to pass underwater obstructions, means engageable with said securing means and disposed adjacent the lower end of said sleeve to lock said swivel bracket from tilting the motor unit relative to the adjusted position thereof with respect to said clamp bracket, a manual lever disposed above said sleeve and forwardly of the motor unit, and means connected to and operated by said lever to actuate said transmission to reverse the propeller and said tilt lock simultaneously in correlation including a rod extending axially through said sleeve and connecting said lever to said tilt lock, whereby said swivel bracket and motor are locked against tilting away from any adjusted normal vertical position only when said transmission reverses said propeller.

9. In an outboard motor supported at its upper end for pivotal movement on a hollow vertical pin and having a shift mechanism at its lower end including an axially horizontally movable control member and a movable actuator, a vertical control shaft extending through said pivot pin and having a lower end adjacent to and engageable with one end of said actuator, and a manual control arm secured to the upper end of said control shaft above said pin for effecting movement of said control shaft and movement of the lower end thereof and of said actuator and said control member in at least one direction.

10. In an outboard motor including a hollow vertical pin supporting the motor for steering movement and having a shift mechanism at its lower end including an axially horizontally movable control member and a movable actuator having offset surfaces adjacent to and engageable with said control member, a control rod extending through said pivot pin and engageable with the forward end of said actuator, and a manual arm secured to the upper end of said control rod above said pin for effecting movement of said rod and movement of said actuator and control member in at least one direction.

11. An outboard motor structure having in combination, a bracket adapted to be attached to a boat, a casing carrying the power head and driving shaft of said motor, a pivot connecting said bracket and casing about the axis of which said casing is swingable, a propeller shaft, a propeller carried by said shaft, a reversing mechanism between said driving shaft and propeller shaft, and means for operating said reversing mechanism including a member coaxial with said pivot.

12. An outboard motor structure having in combination, a bracket adapted to be attached to a boat, a casing, a pivot extending substantially vertically connecting said bracket and casing, a driving shaft journaled in said casing, a propeller shaft, a reversing mechanism between said driving shaft and propeller shaft, said driving shaft being laterally spaced from said pivot, and means for operating said reversing mechanism including a member coaxial with and movable relatively to said pivot.

13. In an outboard motor comprising a steering motor unit including an engine and a underwater propeller and reversing gear unit and a drive shaft housing supporting said engine at its upper end and carrying said gear unit at the lower end thereof; a bracket having an open sleeve pivotally supporting said motor unit for steering movement on a vertical axis, a manual actuating arm for said gear unit disposed adjacent to the upper open end of said sleeve, and a control rod connecting said actuating arm and reversing gear unit movable relative to and extending coaxially with said vertical steering axis through said sleeve.

14. An outboard motor structure having in combination, a bracket adapted to be attached to a boat, a member pivoted to said bracket about a substantially horizontal axis, a casing carrying the power head and driving shaft of said motor, a pivot carried in said member having its axis substantially at right angles to said axis for connecting said casing and member so that said casing is swingable about the axis of said pivot, a propeller shaft, a propeller secured to said shaft, a reversing mechanism for said propeller shaft, means for operating said reversing mechanism including a member coaxial with said pivot and longitudinally movable relatively thereto, a latch pivotally mounted on said first mentioned member, said bracket having means engageable by said latch to prevent swinging movement of said casing away from said bracket, said latch being operated by movement of said last mentioned member.

15. An outboard motor structure having in combination, a bracket adapted to be attached to a boat, a member pivoted to said bracket about a substantially horizontal axis, a casing carrying the power head and driving shaft of said motor, a pivot carried in said member having its axis substantially at right angles to said axis for

connecting said casing and member so that said casing is swingable about the axis of said pivot, a propeller shaft, a propeller secured to said shaft, a reversing mechanism for said propeller shaft, means for operating said reversing mechanism including a second member coaxial with said pivot and longitudinally movable relatively thereto, a latch pivotally mounted on said pivoted member, said bracket including a stop member movable to different positions and adapted to be engaged by said casing for holding the latter in different positions, said bracket also being engageable by said latch corresponding respectively to the different positions of said stop member.

16. In an outboard motor, a dirigible motor unit including an engine, an underwater propeller and a propeller reversing mechanism, a stationary bracket having vertically spaced resilient annular bearing means pivotally supporting said motor unit for relative movement on a vertical steering axis, said resilient bearing means being adapted to absorb the vibration of the motor unit, a control bracket carried by said stationary bracket independently of said motor unit, a control arm carried by said control bracket, and a control rod connecting said control arm and the reversing mechanism and extending coaxially through said annular resilient bearing means whereby said control arm is relatively unaffected by the vibration of the motor unit on its steering axis.
